UNITED STATES PATENT OFFICE.

HARRY G. QUERY, OF SHELBYVILLE, INDIANA.

DESIGN FOR A CALENDAR-FRAME.

47,862.

Specification for Design. Patented Sept. 21, 1915.

Application filed June 18, 1915. Serial No. 34,929. Term of patent 7 years.

To all whom it may concern:

Be it known that I, HARRY G. QUERY, a citizen of the United States, residing at Shelbyville, in the county of Shelby and State of Indiana, have invented a new, original, and ornamental Design for Calendar-Frames, of which the following is a specification, reference being had to the accompanying drawing, forming a part thereof.

The figure is a front elevation of a calendar frame, showing my new design.

I claim:

The ornamental design for a calendar frame, as shown.

HARRY G. QUERY.

Witnesses:

BERT LYONS,
W. C. ADAMS.
